UNITED STATES PATENT OFFICE.

SAMUEL L. S. STICKLE, OF SANTA BARBARA, CALIFORNIA.

DESIGN FOR A DOOR-CHECK.

SPECIFICATION forming part of Design No. 35,240, dated October 29, 1901.

Application filed September 10, 1901. Serial No. 74,959. Term of patent 7 years.

To all whom it may concern:

Be it known that I, SAMUEL L. S. STICKLE, a citizen of the United States, residing at Santa Barbara, in the county of Santa Barbara and State of California, have invented and produced a new and original Design for Door-Checks; and I do hereby declare the following to be a full, clear, and exact description of the same, reference being had to the accompanying drawing, forming a part thereof.

This invention relates to a new and original design for a door-check.

As shown in the accompanying drawing, the design comprises a flat substantially rectangular-shaped member 2. At one end thereof a cylindrical stud or pin 3 projects upwardly, having a diameter equal to the width of the member 2. The other end 4 is bent upwardly at substantially right angles.

5 designates an opening or perforation in the member 2, between the stud or pin 3 and the projection 4.

The essential features of the design are the perforated member 2, the cylindrical portion 25 3, and the upwardly-extending portion 4.

Having thus described the invention, what is claimed as new, and desired to be secured by Letters Patent, is—

The design for a door-check, substantially 30 as shown and described.

In testimony whereof I affix my signature in presence of two witnesses.

SAMUEL L. S. STICKLE.

Witnesses:

CHARLES ALBERT STORKE,
JOHN LIVINGSTON GRIGSBY.
